(57) CLAIM

The ornamental design for a shoe with snake, as shown and described.

DESCRIPTION

A portion of the disclosure of this design patent document contains material to which a claim of copyright protection is made. The copyright owner has no objection to the facsimile reproduction of the patent document or the patent disclosure as it appears in the U.S. Patent and Trademark Office file or records, but reserves all other rights.

FIG. 1 is a top view of a shoe with snake showing my new design;

FIG. 2 is a left side view thereof;

FIG. 3 is a right side view thereof;

FIG. 4 is a top view of the second embodiment of a shoe with snake;

FIG. 5 is a left side view thereof; and,

FIG. 6 is a right side view thereof.

The broken lines showing the shoe environment in the Figures are for illustrative purposes only and form no part of the claimed design.
